(57) **CLAIM**

The ornamental design for a storage box, as shown and described.

DESCRIPTION

FIG. 1 is a front perspective view of a storage box showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view taken from circle 9 in FIG. 2;

FIG. 10 is a right perspective view thereof in another state; and,

FIG. 11 is a right perspective view thereof in still another state.

The dash-dash broken lines in the drawings depict the portions of the storage box that form no part of the claimed design.

The dot-dash broken lines in the drawings depict the boundaries of the enlarged views and form no part of the claimed design.

1 Claim, 11 Drawing Sheets
